SUCTION CLEANER

Donald G. Smellie, Canton, Ohio, assignor to
 The Hoover Company, North Canton, Ohio, a
 corporation of Ohio

Application January 31, 1934, Serial No. 709,058

3 Claims. (CL. 15—16)

The present invention relates to suction cleaners in general and particularly to a new and novel relationship of parts in a suction cleaner. More specifically the invention comprises a suction cleaner in which no relative movement takes place between the fan chamber, the bag and the cleaner handle, the latter being of the usual type which pivots in the operation of the machine. It is an object of the present invention to provide a new and improved suction cleaner. It is another object to provide, in a suction cleaner, a new and improved arrangement of parts in which no bending takes place in the dust bag. A further object is the provision of a suction cleaner in which the cleaner nozzle is fixedly mounted on a supporting frame provided with height-adjusting means, the remainder of the machine being pivotally connected to this frame. Still another object is the provision of a suction cleaner in which pivotal movement takes place at a joint between the fan chamber and the cleaner nozzle. These and other more specific objects will appear upon reading the following specification and claims, and upon considering in connection therewith the attached drawings to which they relate:

Referring now to the drawings in which preferred embodiments of the present invention are disclosed, and in which the same reference character refers to like parts throughout:

Figure 1 is a longitudinal cross section through a cleaner constructed in accordance with the present invention;

Figure 2 is a front view of the cleaner shown in Figure 1;

Figure 3 is a side elevation on a reduced scale, the cleaner being shown in the storage position in dotted lines;

Figure 4 is a section upon the line 4—4 of Figure 1 through the cleaner handle;

Figure 5 is a section through the pivotal connection in the cleaner;

Figure 6 is a side view of the cleaner, partly in section, showing dusting tools connected for off-the-floor cleaning;

Figure 7 is a front view of a second embodiment of the invention;

Figure 8 is a section upon the line 8—8 of Figure 7;

Figure 9 is a side elevation of the embodiment of the invention shown in Figures 7 and 8;

Figure 10 is a section upon the line 10—10 of Figure 9.

In the usual suction cleaner constructed for on-the-floor cleaning the nozzle, the fan chamber, including the fan, and the driving motor form the

main body of the machine which is usually mounted upon front and rear supporting wheels. A pivoted handle is connected somewhere to this body and to its upper end is connected the dust bag which is open at its lower end to the exhaust outlet of the fan chamber. In the operation of this type of machine as the cleaner is moved back and forth upon the surface covering by the operator, the handle pivots relative to the main body of the machine, and the dust bag, being connected to the handle at its upper end, bends or flexes at its lower point of attachment at the exhaust outlet of the cleaner. While this bending of the bag has no particularly undesirable effect if the dust bag be made of cloth, it has been discovered that when paper bags are used this repeated flexing results in bag failure.

In suction cleaners constructed in accordance with the present invention no flexing is produced in the bag in cleaner operation. This result has been obtained without sacrificing cleaner efficiency through the use of parts which are too light to be capable of functioning in their intended manner. In applicant's construction each part functions as in the ordinary cleaner with no sacrifice in efficiency and the parts have been so arranged and related that no appreciable cleaner weight is supported by the operator.

Referring again to the drawings, and Figures 1 to 6, inclusive, in particular, a suction cleaner constructed in accordance with the present invention is disclosed. The nozzle 1 is formed integrally with the supporting frame 2 which is movably supported upon spaced pairs of front and rear supporting wheels 3, 3 and 4, 4, respectively. The front wheels 3, 3 are pivotally mounted upon a transversely extending crank shaft 5 which is provided with height-adjusting means comprising a fixed positioned manually rotatable member 6 which extends in screw threaded relationship with a vertical shaft 7 which is directly connected to one end of the crank shaft for the purpose of adjusting its angular position and accordingly the height of the nozzle 1 above the surface covering undergoing cleaning.

The driving motor 8 is formed with an enclosing casing and is positioned within spaced relation to the main casing 9 which is reduced at its forward end to form a fan chamber 10. The suction-creating fan 11 is carried by the extended motor shaft and is positioned within this chamber 10, functioning in the operation of the machine, to draw air through the eye 12 of the fan chamber and exhaust it rearwardly into the dust

bag through the circular passageway formed between the motor 8 and casing 9.

The casing including the fan chamber 10 is formed immediately outside the eye 12 as a transversely extending passageway or conduit 14 which extends in both directions at the sides of the eye 12, being flanged at its ends as indicated at 15, 15. Each end flange 15 is provided with an internal circular seat 16, as is clearly illustrated in Figure 5, and within this seat extends a circular seat member 17. These seats 17, 17 are mounted on the inner ends of the rearwardly extending air conduits 18, 18 which extend upwardly and rearwardly from the nozzle mouth to a position between the front and rear supporting wheels. Suitable air seals 19 space each seat 16 from its seat member 17 and provide an air tight joint yet one permitting rotation between the two parts.

Control of the angular relationship between the suction-creating means and its supporting frame, in the absence of a positive pivoting force by the operator, is exerted by a spring-pressed detent 20 mounted on frame 2. Detent 20 includes a roller 21 at its end which rides upon the edge of an arcuate sector 22 carried by conduit 14. The sector edge is formed, at spaced angular positions, and in the order given, with a seat 23, an elongated seat 24, and a second seat 25 similar to seat 23. With the cleaner within its usual working range, the roller detent 21 moves between the shoulders defining the limits of the elongated seat 24 preventing unintended movement from this range. With the machine in the storage position, that shown in dotted lines in Figure 3, the detent seats within the seat 23, while with the machine in the lower horizontal position the detent seats within the seat 25. The detent is removable from each of the seats by a sufficient pivoting force exerted upon the construction 40 which would, of course, come from the cleaner handle.

The cleaner handle is indicated by the reference character 26, and is seen to extend parallel to the motor axis and adjacent the upper side of the bag 13. Its lower end seats within a socket 27 formed integrally on the main casing 8 and the incoming power leads 28, 28 to the motor extend downwardly through this handle, through a suitable plug connection 27a within the socket 27, and through a suitable conduit and support member 29 into the motor 8. It is seen that no relative pivotal movement is possible between the handle and the main casing of the cleaner, and that the suction-creating means, the bag and the handle pivot as a unit about the transverse axis through the seats 16, 16 on the conduit 14.

The cleaner is so constructed that, with the suction-creating means pivoted to the lower horizontal position with the detent 21 within the seat 25, dusting tools may be attached to the suction-creating means. To make this possible the transversely extending passageway 14 is provided centrally opposite the eye 12 with a removable cover plate 30 which is normally held in place through 65 being snapped over the projecting heads of screws 31, 31. With the main body of the machine positioned with its axis horizontal and the cover plate 30 removed, the eye 12 of the fan chamber is exposed between the space conduits 18, 18 on the nozzle. The converter 32 can then be inserted through the passageway and into seating relationship with eye 12, the converter being retained in place by a leaf spring 33 which snaps over the head of the upper screw 31.

75 Referring now to Figures 7 to 10, inclusive, the

second preferred embodiment of the invention is disclosed. In this embodiment the nozzle 1, its supporting frame 2, and the wheels 3, 3 and 4, 4 are related as in the first embodiment. The relationship between the transverse conduit 14 and the conduits 18, 18 is also the same as that previously described, and the position-controlling means are provided. In the present embodiment, however, the conduit 14 is formed on a fan chamber 40 provided with a definite tangential 10 exhaust outlet 41 which extends adjacent and parallel to the handle 26, which is itself fixedly seated in the socket 44 on the chamber. To this outlet 41 is secured the dust bag 42 which extends along and at the side of the handle. As in 15 the first embodiment no movement takes place between the bag and the handle. As the exhaust passageway does not pass around the motor in this embodiment the motor 43 is exposed to view being secured to the back of the fan chamber 40. 20 The motor functions, as in the previous embodiment to drive a suction-creating fan, here indicated by the reference character 44.

I claim:

1. A suction cleaner comprising a nozzle, means 25 movably supporting said nozzle for movement over a surface covering, a fan chamber formed with a transversely extending air conduit immediately adjacent its eye and communicating therewith, said conduit being interiorly connected to 30 and mounted on said nozzle for rotation about a horizontal axis transverse to the direction of cleaner movement, said conduit being formed with an opening which faces forwardly with said conduit rotated to a certain position, movable 35 means normally closing said opening, said nozzle, said conduit and said opening being shaped and arranged to permit the insertion of a dusting tool connection into said conduit through said opening, a fan in said chamber, a driving motor connected to said fan, a handle rigidly mounted relative to said fan chamber, and a bag connected to the exhaust outlet of said chamber and supported by said handle.

2. A suction cleaner comprising a nozzle formed with spaced air passageways extending rearwardly from the mouth thereof, a fan chamber formed with an air conduit communicating therewith and extending transversely to the major axis of said chamber, said conduit being interiorly connected 50 to and mounted on said nozzle between said air passageways for rotation about a horizontal axis transverse to the direction of cleaner movement, said conduit being formed with an opening which faces forwardly between said air passageways with said conduit rotated to a certain position, manually movable means normally closing said opening, said opening being adapted to receive a dusting tool connection, a fan in said chamber, a driving motor connected to said fan, a handle rigidly mounted relative to said fan chamber, and a bag connected to the exhaust outlet of said chamber and supported by said handle.

3. A suction cleaner comprising a nozzle formed with spaced air passageways extending rearwardly from the mouth thereof, a fan chamber formed with an air conduit communicating therewith and extending transversely to the major axis of said chamber, said conduit being interiorly connected to and mounted on said nozzle between 65 said air passageways for rotation about a longitudinal axis parallel to itself, said conduit also being formed with an opening aligned with the eye of said fan chamber and adapted to receive a dusting tool connection, said opening facing for- 70 75

wardly between said passageways in certain angular positions of said conduit to permit the insertion of said connection, manually movable means normally closing said opening, cooperating means on said nozzle and on said fan chamber exterior of said conduit retaining said conduit in certain

angular positions and ranges of positions against unintended displacement, a fan in said fan chamber, a driving motor connected to said fan, a handle rigidly mounted relative to said fan chamber, and a bag connected to said exhaust outlet.

DONALD G. SMELLIE.

CERTIFICATE OF CORRECTION.

Patent No. 2,046,658.

July 7, 1936.

DONALD G. SMELLIE.

It is hereby certified that error appears in the printed specification of the above numbered patent requiring correction as follows: Page 1, second column, line 48, after "within" insert in; page 2, second column, line 72, claim 3, strike out the words "parallel to itself"; and that the said Letters Patent should be read with these corrections therein that the same may conform to the record of the case in the Patent Office.

Signed and sealed this 13th day of October, A. D. 1936.
